UNITED STATES PATENT OFFICE

HENRY W. PETERS, OF BOSTON, MASSACHUSETTS

FINGER RING AND THE LIKE

Application filed September 16, 1929. Serial No. 393,048.

This invention relates to finger rings and the like, one of the objects being to provide improved means whereby a stone or the like can be held properly assembled with the ring without requiring the use of soft solder which, as is well known to those skilled in the art, soon separates, necessitating frequent repairs.

Another object is to provide a means for fastening stones in position without danger of breaking them.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a plan view of a ring having the present improvements combined therewith.

Figure 2 is a side elevation thereof.

Figure 3 is a section on line 3—3, Figure 1.

Figure 4 is an edge view of a signet plate.

Figure 5 is a plan view of two stones adapted to be retained by the signet plate.

Figure 6 is a view similar to Figure 3 showing a modified construction.

Figure 7 is an edge view of a modified form of signet plate.

Referring to the figures by characters of reference, 1 designates a ring or other article of jewelry having a base 2 which, in the structure illustrated, is formed in its outer surface with parallel dove-tail grooves 3 open at their ends. It is to be understood that any desired number of these grooves can be used and said grooves can be disposed at any desired angles relative to each other.

The stones or the like to be inserted in the grooves have been indicated at 4 and are so shaped as to fit snugly in the grooves with their ends flush with those faces of the ring or the like through which the ends of

the grooves open. The side edges of the stones or other objects 4 are adapted to be overhung by the walls of the grooves so that it is thus impossible to insert or remove the parts 4 except by sliding them longitudinally.

Each of the objects 4 is provided, in one edge portion, with a notch 5 produced in any manner desired and this notch can be of any preferred contour.

A signet plate has been shown at 6 and can be provided with any desired design on one surface. This signet plate can have opposed corner portions formed with upwardly projecting nodes or extensions 7.

In assembling the parts of the ring the signet plate 6 is fastened to the ring or the like by hard solder at a point between the grooves 3. Thereafter the stones or other objects 4 are slid into the grooves until the notches 5 are brought to positions directly under those corners of the signet plate on which the nodes or projections 7 are formed. By means of a hammer or other suitable tool these corner portions of the signet plate are then hammered downwardly so that metal will be displaced into the notches 5 which will be partly or entirely filled so as to prevent the stones from shifting longitudinally. Thus the stones will be held securely in position and cannot be removed. Furthermore the means for holding the stones in place will not be visible. As it is possible to attach the signet plate before the stones are inserted, hard solder, requiring intense heat, can be used and, therefore, the signet plate will not become detached.

Instead of attaching the signet plate by means of solder, said plate can be formed with downwardly projecting nodes or extensions 8 as shown at 8 in Figures 6 and 7, the plate 9 being provided with a pin 10. After the stones have been placed in the grooves, the signet plate is mounted with its projections 8 extending into the notches 5 and pin 10 extending through an opening 11 in the ring or the like. The inner end of the pin is then upset as shown in Figure 6 so that the signet plate will be held against displacement and

this plate, in turn, will hold the stones against withdrawal from their grooves.

As before stated any desired arrangement of grooves can be used. Furthermore, instead of having dovetail grooves, the grooves can be formed with only one overhanging wall for each groove. It is merely essential that the grooves be so shaped as to allow the stones to be inserted longitudinally thereinto and at least partly retained by one wall of each groove.

What is claimed is:

1. An article of jewelry including a base having a groove open at its ends, an object insertable endwise into and adapted to fit snugly within the groove, said object having a notch or the like in one edge, a signet plate soldered on the base and having a portion overlying the notched portion of the object, and means depending from the signet plate and seated in the notch for holding said object against withdrawal.
2. An article of jewelry including a base having a groove, an object insertable into and adapted to fit snugly within the groove with its upper face flush with the corresponding face of the base, a signet plate soldered on the base and having a portion overlying the inserted object to hold it against upward withdrawal from the groove, and means integral with the signet plate and projecting into the inserted object for holding said object against sliding movement longitudinally of the groove.
3. An article of jewelry including a base having a groove therein, an object slidable into the groove and flush with the grooved face of the base, a signet plate resting on and joined to the base, said plate having a portion overlying the inserted object, thereby to prevent the object from being lifted out of the groove, and means carried by the signet plate and projecting into said object for holding the object against sliding withdrawal longitudinally of the groove.
4. The herein described method of making an article of jewelry which consists in grooving a base and then applying a signet plate to the face of the base so that a portion thereof overhangs the groove, subsequently sliding a stone into the groove and under the overhanging portion of the signet plate, the corresponding faces of the stone and the base being flush, and finally displacing inwardly a portion of the overhanging part of the signet plate so as to enter a notch in the stone and hold the stone against longitudinal sliding movement.

In testimony that I claim the foregoing as my own, I have hereto affixed my signature.

HENRY W. PETERS.
